DESIGN FOR AN AUTOMOBILE

Gaston Grummer, Clichy, and Guillaume Busson,
Neuilly, France

Application April 25, 1934, Serial No. 51,522

Term of patent 7 years

To all whom it may concern:

Be it known that we, Gaston Grummer, 39
bis rue Martre, Clichy (Seine), France, and Guillaume
Busson, 5 Avenue Sainte Foy, Neuilly (Seine), France, have invented a new, original,
and ornamental Design for Automobile, of which
the following is a specification, reference being
had to the accompanying drawings, forming part
thereof.

Figure 1 is an elevational view of the automobile
in running condition, showing our new design.

Figure 2 is a top plan view of said body.

Figure 3 is a front view thereof.

Figure 4 is a rear view thereof.

Figure 5 is a fragmentary perspective view
showing one door of said automobile body, said
door being shown in the open position.

Fig. 6 is a front perspective view of the
automobile.

We claim:

The ornamental design for an automobile as
shown.

GASTON GRUMMER.
GUILLAUME BUSSON.
